UNITED STATES PATENT OFFICE.

JOHN A. WICKSON, OF VICTORIA, BRITISH COLUMBIA, CANADA.

BUILDING BLOCK.

1,416,919.

Specification of Letters Patent. Patented May 23, 1922.

Application filed September 12, 1921. Serial No. 499,887.

To all whom it may concern:

Be it known that I, JOHN A. WICKSON, a citizen of the Dominion of Canada, residing at Victoria, in the Province of British Columbia, Canada, have invented certain new and useful Improvements in Building Blocks, of which the following is a specification.

This invention relates to a hollow building block preferably made from terra cotta or the like. The improvements are directed to a form of block that may conveniently be applied to effectively bond together in a wall, whether it is of single or multiple block thickness, and that the core spaces will be vertically disposed and registering, affording facility for reinforcement of the wall with uninterrupted columns of concrete filling certain of the core spaces.

It is also an important feature of the block that whether built in a wall of single or multiple block thickness, there is no direct communication between the outer and inner faces of the wall, but that each connection between the faces will be directly insulated by an ample air space.

The wall cavities being vertical provide for ventilation, and thus condensation of moisture on their inner surfaces is avoided. They also afford facility for the conduction of service wires or pipes throughout the building.

The invention is fully described in the following specification, reference being made to the drawings by which it is accompanied, in which:

Fig. 1 is a plan showing from left to right the evolution of the block from its primary or simple form.

Fig. 2 is a face elevation of the same to an enlarged scale.

Fig. 3 is a sectional plan showing the vertical grooves which may be provided on the outer faces of the block for the retention of stucco or plaster and on the joint walls for the better adherence of the joint cement.

Fig. 4 is a cross section of a block on the line 4-4 in Fig. 2.

Fig. 5 shows in perspective the application of the block to a wall of single block thickness.

Fig. 6 is a similar view of a multiple block wall showing the introduction of reinforcing wires and the manner of supporting the flooring joints.

Fig. 7 is an isometric view of a block

showing grooves connecting the core spaces which are cement filled.

Figures 8 and 9 are detailed views of modifications hereinafter referred to.

In its simplest elements the building block consists of two integral portions 2 and 3 forming opposite faces of the block, the length of the exposed face of 3 being double that of 2 and projects an equal distance beyond it at each end. The portions 2 and 3 are alike in depth and thickness and their bedding faces are in the same plane.

The longer portion 3 of this elementary form of block, as shown to the left in Fig. 1, has two core spaces 7 through its depth, which spaces are separated by a cross partition at the midlength of the block, and the shorter portion 2 has a similar core space 7.

These core spaces are thus staggered in relation to one another and effectively prevent the percolation of moisture directly through the material of the block from one face of it to the other, as the end walls of the shorter portion 2 are directly opposite the air spaces 7 of the longer portion 3, and the cross partition between the air spaces 7 of the longer portion 3 are immediately opposite the air space 7 of the shorter portion 2.

Further, when the blocks are built in a wall, the end walls of the longer portion 3 are immediately opposite the air spaces 7 of the longer portion 3 of the contiguous blocks on each side.

Another important feature of this construction lies in the fact that when the blocks are coursed in a wall and the ends break joint with one another, the several core spaces 7 will register with one another to satisfy the several desired requirements, as set forth in the preamble to this specification.

While the description so far is of the primary or elementary form of block, in the preferred form set forth toward the right of Fig. 1, portions 4 are removed from each end of 2 and 3 within the exposed faces, leaving projections 5 to maintain outwardly the full length of these faces, so that when the blocks are placed end to end with the shorter or header face 2 of one in the plane of the longer or stretcher faces of the contiguous blocks, cavities 4 are revealed between the ends of the adjacent blocks.

To enable these cavities 4 to be maintained through the adjacent courses, where the middle of the superposed block is bonded

over the ends of the block beneath, the core spaces 7 in the longer portion 3 are shortened and a core space 6 is carried between them through the depth of the block in the middle of the longer portion 3 of the same, which core space corresponds in length and breadth to the space 4 4 revealed between the ends of adjacent blocks. The spaces 4 4 and 6 of the several courses will thus register with one another throughout the height of the wall, without impairing the vertical registration of the spaces 7 before referred to.

With this block walls of single or of multiple block thickness may be built and as the core spaces 4 4 and 6 are in vertical alignment, these spaces may be filled with cement or cement concrete as the work proceeds, which filling serves not only to securely bond and key the blocks together, but also reinforces the strength of the wall. Metal reinforcement 13 may also be imbedded in the concrete which is filled into these core spaces to further increase the strength where such is considered desirable or necessary.

A shoulder 14 is provided in each corner where the portion 2 is joined to 3 to maintain the blocks in correct position endwise, where, as in Fig. 6, a multiple block wall renders it necessary for the shorter portion 2 of one block to be introduced between the shorter portions of adjacent blocks.

Along the medial line of the block in both bedding faces thereof, a groove 8 is formed, which groove is filled with cement while the wall is being built, thereby ensuring a more effective bond between the adjacent blocks and their reinforcing columns of concrete in 4 4 and 6. Along these grooves 8 a reinforcing wire 8* (Figure 4) of metal may be carried where such extra reinforcement is considered necessary.

The core spaces 4 4 and 6 may also be connected by grooves or channels 15 into which the cement will flow as the core spaces are being filled.

A pointing groove 9 may be formed along the lower edge of the outer faces of 2 and 3 to receive pointing cement where the outer face of the wall is not to be stuccoed.

Where the wall is to be stuccoed or plastered the outer faces of 2 and 3 may have vertically disposed recesses 10 to more effectively retain the same.

The end walls of the portions 2 and 3 may have similar vertically disposed recesses 11 to provide a more effective hold for the reinforcing concrete and a dove-tailed vertical recess 12 may be provided on the back faces of the portion 3, which recesses will register with those of the adjacent blocks, and being filled with cement as the work proceeds will bond the blocks against endwise movement apart.

The form of the block not only lends itself to the construction of a strong and well

bonded wall of any desired thickness and one which may be reinforced by both concrete and metal, and that without the use of skilled labour, but the form has a most important advantageous feature in the fact that there is no direct connection between the outer and inner faces of the wall, through which moisture may percolate. Whether the wall is of single or multiple thickness an ample air space or air spaces are interposed between every cross wall connection.

The form is one that is favourable to strong corner connection requiring the use of only a limited number of shoulders 14, the form of which is extremely simple but does not embody any patentable features. A simple filler block 16 is also used to maintain the flooring or roofing joists in the upright position, as shown in Fig. 6.

Although described as specifically designed for manufacture in terra cotta or the like, the form of block is equally applicable with possibly slight modification for manufacture in cement or cement concrete.

The block is particularly applicable to the construction of silos by virtue not only of the sufficient air space for keeping the interior cool but on account of its effective bond and the facility for its reinforcement.

The outer faces of 2 and 3 may be convexly or concavely curved see Figure 8, or may be angularly sloped without departing from the essential features of the invention see Figure 9.

Having now particularly described my invention, I hereby declare that what I claim as new and desire to be protected in by Letters Patent, is:

1. A building block the ends of which are half-lapped in vertical planes and having end shoulders the lap extensions of both ends being toward the same face of the block, each end of each lap extension and each end shoulder having portions removed within the outer faces of the blocks that will form recesses between the ends of adjacent blocks, and that portion of the block on which are the lap extensions having in its midlength a core space through its depth, the dimensions of which correspond with those of the recesses formed between the ends of adjacent blocks.

2. A building block, each end of which is formed as a half-lap in vertical planes and provided with end shoulders between the bedding faces of the block, the lap extensions of both ends being toward the same face of the block, the body of each block having core spaces through its depth those which are toward one face of the block being staggered in relation to that of the other, and both bedding faces of the block having a lengthwise groove from end to end which grooves are in connection with certain of the core spaces.

3. A building block, the ends of which are half-lapped in vertical planes and provided with end shoulders, the lap extensions of both ends being toward the same face of the block, each end of each lap extension and each end shoulder having portions removed within the outer faces of the blocks that will form recesses between the ends of adjacent blocks, and that portion of the blocks on which are the lap extensions having in its midlength a core space through its depth, the dimensions of which correspond with those of the recesses formed between the ends of adjacent blocks, both bedding faces of the block having a lengthwise groove extending from end to end, which grooves connect with the medial core space and with the ends of the block.
4. A building block, each end of which is formed as a half-lap in vertical planes between the bedding faces of the block, the lap extension of both ends being toward the same face of the block, the body of each block having core spaces through its depth,
- the core spaces which are toward one face of the block being staggered in relation to that of the other, the faces of the end overlaps having vertically disposed recesses which connect with one or other of the core spaces.
5. A building block, the ends of which are half-lapped in vertical planes the lap extensions of both ends being toward the same face of the block, each end of each lap extension and each end shoulder having portions removed within the outer faces of the blocks that will form recesses between the ends of adjacent blocks, and that portion of the block on which are the lap extensions having in its midlength a core space through its depth, the dimensions of which correspond with those of the recesses formed between the ends of adjacent blocks, the faces of the overlapped ends having vertically disposed dovetailed recesses which are connected by the lengthwise grooves to the medial core space and ends of the block.

In testimony whereof I affix my signature.
JOHN A. WICKSON.
